A. G. SMITH.
FOLDING BED.
FILED JULY 18, 1921.

Fig. 1.

UNITED STATES PATENT OFFICE.

ARTHUR GARFIELD SMITH, OF LOS ANGELES, CALIFORNIA.

FOLDING BED.

Application filed July 18, 1921. Serial No. 485,589.

To all whom it may concern:

Be it known that I, ARTHUR GARFIELD SMITH, a citizen of the United States, residing at Los Angeles, in the county of Los Angeles and State of California, have invented new and useful Improvements in Folding Beds, of which the following is a specification.

This invention relates to a folding bed and particularly pertains to a bed adapted to be folded into a compact form for transporting.

An object of the invention is to provide a bed of the above character that is particularly adapted for use by motorists, campers and others requiring a bed that may be compactly folded and is of light weight and readily carried.

Another object of the invention is to provide a bed of the above character embodying a foldable frame or support of lazy-tong construction and a canvas stretcher adapted to be stretched over the frame, the beam members forming the frame being disposed relative to the normal stresses created by weight upon the stretcher to provide extreme rigidity.

Another object of the invention is to provide a folding bed of the above character in which the frame may be folded or expanded without the necessity of disconnecting fastenings of any kind and in which all parts are secured together and cannot be misplaced.

The invention is illustrated by the accompanying drawings, in which:

Figure 1 is a view in perspective of the bed in its fully erected form, showing a part of the stretcher broken away to reveal underlying parts.

Figure 2 is a view in side elevation of the frame in its partially folded form.

Figure 3 is a view in end elevation of the frame partially folded.

Figure 4 is a view in enlarged detail section as seen on the line 4—4 of Figure 1.

Figure 5 is a detail in perspective of a tie rod.

Figure 6 is a detail in section as seen on the line 6—6 of Figure 1.

More specifically 5 indicates a foldable frame adapted to be expanded to serve as a support for a stretcher 6 which is normally drawn taught across the frame. The stretcher 55 may be of any suitable construction adapting it for this purpose but is here shown as

comprising a flexible sheet 7 of canvas or other suitable material which is provided at its ends with transverse rigid cross bars 8, to which the ends of the sheet are secured. 60

The frame is formed of two parallel side members 9—9 which comprise a plurality of struts 10, here shown as four in number arranged in lazy-tong construction. The struts are pivoted together in pairs at their centers by means of bolts 11, passing therethrough. The lower ends of the struts are designed to rest on the surface upon which the frame is placed and affords a three point support for each foldable side member; the lower connected ends of the struts bearing on the surface intermediate the lower free ends of the struts. The pivotal connections of these side members adapt them to be readily folded along the horizontal plane as 75 shown particularly in Figure 2. The side members are held against expanding beyond the requisite length by means of a tie 12, which is formed of two metal strips 13 pivoted together adjacent their ends to permit 80 of the tie being folded at its center when the side members are folded. One of the pieces 13 is provided with a lug 14 adapted to engage the other piece when the tie is fully extended, to prevent any tendency of the 85 tie to buckle downwardly.

The two side members of the frame are held spaced apart the requisite width by means of a pair of foldable braces 15 which comprise four crossed members 16 formed 90 preferably of metal strips and pivoted at the point where each two members cross as well as pivoted to each other adjacent their inner ends by means of rivets 16', the frame thereby being foldable in its transverse dimension as shown by Figure 3. Each foldable brace is disposed on the same plane as the struts of the side members and each lower end 17 of the brace is pivotally secured to one of the struts by pivots 17' and is placed 100 between the pivoted ends which rest upon the ground at the center of the frame. The upper ends of each brace on either side carry collars 18 which are pivotally connected to the brace member by pivots 18' and loosely 105 encompass the strut and are slidable thereon. Inasmuch as the distance between each upper and lower end of the brace increases as it is folded this collar allows the upper end to move along the strut relative to the other 110 end which is fixed relative to the strut. This construction permits of the braces being

folded without being disengaged from the frame and thereby permits of the frame being folded upon its transverse dimension so that the entire frame may be folded to occupy the minimum space.

When the frame is erected the stretcher is fixed thereto in any suitable manner but for this purpose the bars 8 are provided with round ends 19, adapted to enter corresponding holes 20, provided in the upper ends of the side members of the frame. To permit of using relatively light cross bars in the stretcher without sacrificing strength the stretcher is provided with a pair of truss rods 21 pivotally connected to the cross bars at the center thereof by a bolt 22 and provided at either end with a wing-nut 23. As a means for securing these truss rods to the frame slots 24 are provided in the upper ends 20 of the side members.

To fold the bed the wing-nuts which abut against the side members of the frame as shown particularly in Figure 4, are loosened so that the trusses may be raised out of the slots. The cross bars are removed from the holes in the side members by spreading the frame slightly. The stretcher is thus readily removed from the frame. The frame is then folded by first forcing the ends toward one another while it rests upon the ground until it is folded to its minimum longitudinal dimension. Figure 2 shows this operation as partially completed.

The frame on being pressed together transversely as shown in Figure 3 causes the braces to collapse, while the collars 18 being slideable upon the struts of the side members allow this brace to collapse gradually until the entire frame occupies the minimum space. The stretcher may be wrapped around the folded frame to form a compact bundle to facilitate transporting.

As a means for adjusting the extent of opening of the lazy-tong, the tie strips 13 are formed with a series of perforations 25 adjacent their outer ends with one of which each bolt 11 is engaged according to the length of span of the tie desired.

In order to prevent sagging of the stretcher as by springing the struts, a second tie member 26 is provided for each frame 9 which comprises a pair of rods 27-28 piv-

oted together at 29 and having hooks 30-31 at their outer ends adapted to be engaged with the cross pieces 8. The tie member 26 is arranged to seat on the bolt 32 by which the upper portions of the inner struts are connected together; the tie being disposed between the struts, as shown in Figure 6, and the wing nut 33 tightened to clamp the tie rod between the struts. This arrangement supports the tie rods against depression and against being bent at the pivot 29, and also holds them against side movement.

I claim:

1. In a folding bed, a flexible sheet, a transverse bar secured to each end of said sheet, a pair of side frames, each comprising a pair of crossed struts pivotally connected together with the pair of struts pivoted together to form lazy-tongs, said transverse bars being carried by the end portions of said frame members and a pair of tie members connecting the transverse bars for limiting the spread of the lazy-tongs.

2. In a folding bed, a flexible sheet, a transverse bar secured to each end of said sheet, a pair of side frames, each comprising a pair of crossed struts pivotally connected together with the pairs of struts pivoted together to form lazy-tongs, said transverse bars being carried by the end portions of said frame members, a pair of tie members connecting the transverse bars for limiting the spread of the lazy-tongs, and means for clamping said tie rods relative to the lazy-tongs.

3. In a folding bed, a flexible sheet, a cross bar at each end of said sheet, a pair of lazy-tong frames, means for detachably connecting said cross bars to the end portions of said frames, a pair of tie rods having hooks at their outer ends adapted to engage the cross bars, and means for clamping said tie rods to said lazy-tongs.

4. In a folding bed, a flexible sheet, a cross bar at each end of said sheet, a pair of lazy-tong frames embodying struts having openings to receive the ends of said bars and truss rods connected to the cross bars and means for adjustably connecting said truss rods to the lazy-tongs.

ARTHUR GARFIELD SMITH.
